DECURLING ATTACHMENT FOR HOSIERY
SEAMING MACHINESFrank G. Reuther, Philadelphia, Pa., assignor to
H. C. Aberle Company, Philadelphia, Pa., a
corporation of Pennsylvania

Application January 30, 1935, Serial No. 4,144

9 Claims. (Cl. 112—20)

This invention relates to a device for removing curl from the selvedge or cut edges of knitted fabrics, particularly the longitudinal or walewise extending edges thereof prior to joining said edges together or to passing the edges into the feeding mechanism of a sewing, looping, or other seaming machine, whereby such edges will be presented to the seaming machine in flat parallel relation to each other.

10 The invention more specifically relates to improvements in decurling devices such as those used in connection with the seaming together of the edges of flat full fashioned hosiery blanks, such, for example, as the device shown in U. S. Letters Patent to Lansing Onderdonk No. 1,282,458, dated October 22, 1918.

15 The improvements forming the subject matter of the present invention are particularly adapted for use in seaming hosiery which embodies certain features disclosed in the prior U. S. Patent to John Hadfield No. 1,444,684 dated February 6, 1923, and which is finished in accordance with the practice of seaming hosiery, so as to present the smooth side of the fabric 20 outermost when the stocking is being worn, which practice is disclosed in U. S. Patent No. 1,849,783, issued to Edwin B. Beacham under date of March 15, 1932.

25 The decurling device disclosed in the Onderdonk patent is commercially employed for seaming together the opposite selvedge edges of full fashioned hosiery blanks which have been made in the usual manner and wherein the completed stocking is adapted to be worn with the rough side out, i. e., the face whereon the needle loop wales of the fabric are prominent, and which in the Beacham patent is referred to as the rough side of the fabric.

30 The Beacham patent refers to the seaming of the edges of a stocking blank together in such a manner that when the stocking is being worn the rough side of the fabric is on the inside and the smooth side, i. e., the face on which the sinker loop wales of the fabric are prominent, 35 is on the outside.

35 The Hadfield patent refers to the production of full fashioned stockings under a process wherein the top portion of a stocking, including the usual double ply or turned welt and a depending portion of the stocking leg composed of single thickness fabric, either with or without open-work or lace designs formed therein, is produced on a circular knitting machine provided with automatic welt-turning mechanism, and 40 wherein such circular knit upper portion of the

stocking is subsequently split, walewise, and a course of stitches forming part of the circular knit top is topped on to the needles of a flat full fashioned hosiery knitting machine and to which the leg of the stocking is subsequently 5 knit.

In carrying out the above feature of the Hadfield patent, the split circular top is normally topped on to the needles of the flat hosiery knitting machine with the needle wale or rough 10 side of the stocking fabric down, whereby, in the successive courses of the leg which are knitted onto the applied top, the needles of the flat knitting machine, in drawing their stitches downwardly through the stitches of the circular 15 knit top which are then hanging on the needles of the flat machine, produce the needle loop wales correspondingly on the under side of the stocking blank, so that in the completed stocking 20 formed the line of interknitting of the circularly 25 formed top with the flat knit leg is not apparent.

When combining the above noted features of the Beacham and Hadfield patents in a single stocking, the circular knit top is applied to the needles of the flat knitting machine with the 25 rough or needle wale side of the fabric uppermost, consequently when the leg portion of the stocking is interknit with the circular knit top the needle wales of the leg are on the underside of the fabric, consequently in the finished blank 30 the rough side of the top faces in one direction while the rough side of the leg faces in the opposite direction.

Under the above noted circumstances, when the stocking blank is seamed in the manner to 35 place the so-called rough side of the leg fabric on the inside when the stocking is worn the so-called rough side of the fabric forming the top of the stocking is on the outside as usual. This is advisable in order that the suture at which the 40 inner lap of the turned welt connects to the outer lap of the welt and to the single ply fabric or shadow welt at the top of the leg of the stocking and which is formed by the automatic 45 welt-turning mechanism of the circular knitting machine will be on the inside of the stocking when worn and any lacework which may be included in the turned welt, the shadow welt below the turned welt or both of the circular knit top portion of the stocking will be right-side out 50 on the stocking when being worn.

It is characteristic of knitted fabrics that, regardless of whether the fabric be provided with a selvedge edge or whether the fabric has a raw cut edge, the fabric immediately adjacent the 55

edge thereof tends to curl in a direction toward the smooth side, that is, toward the sinker wale side, thereof. Consequently in a stocking blank embodying the above noted features of the Hadfield and Beacham patents, the edges of the fabric constituting the foot and leg of the stocking curl in one direction while the edges of the upper portion of the stocking which have been formed on the circular knitting machine curl in the opposite direction.

The decurling device disclosed in the Onderdonk patent is adapted for taking the curl out of the edges of a stocking blank wherein the curl on the fabric is entirely in the one direction, such as in a stocking produced in its entirety on a flat knitting machine. Consequently, in stockings of the inside-out type, such as that disclosed in the Beacham patent, the decurling device of the Onderdonk patent is not operable in the form disclosed in said patent; and in stockings combining the above noted features of the Hadfield patent, insofar as the circular knit top of the stocking is concerned, and the feature of the Beacham patent, insofar as the turning in-side-out of the leg of the stocking is concerned, the decurling device shown in the Onderdonk patent is effective only in the seaming of the upper part of the stocking which has been formed on the circular knitting machine.

The object of the present invention is to construct a decurling device which is adapted to remove the curl from the edges of the stocking blank embodying the above noted features of the Hadfield and Beacham patents, in a single operation, from end to end of the stocking, that is, from the toe of the stocking to the extreme point of joining of the edges of the inner ply of the turned welt of the stocking.

The device forming the subject of the present invention will be fully disclosed hereinafter, reference being had to the accompanying drawings; of which:

Fig. 1 is a side view of a completed stocking embodying certain features of the Hadfield and Beacham patents, as noted above;

Fig. 2 is a transverse sectional view taken on the line 2—2, Fig. 1;

Fig. 3 is a face view of the blank prior to the seaming of the opposite edges thereof for producing a stocking similar to that shown in Fig. 1;

Fig. 4 is a transverse sectional view of the blank taken on the line 4—4, Fig. 3;

Fig. 5 is a transverse sectional view of the blank taken on the line 5—5, Fig. 3;

Fig. 6 is a transverse sectional view of the blank taken on the line 6—6, Fig. 3;

Fig. 7 is a transverse view of the blank similar to Fig. 5 but showing the blank folded along its longitudinal axis and prior to the seaming of the opposite longitudinal edges of the blank together;

Fig. 8 is a transverse section of the blank after folding on its longitudinal axis and corresponding to the same portion of the blank as illustrated in Fig. 6;

Fig. 9 is a transverse sectional view of the folded blank after over-seaming of the coinciding edges of the blank and prior to the stocking being turned inside out in its completed form as illustrated in Figs. 1 and 2;

Fig. 10 is a side elevation of a conventional over-seaming machine, such as that illustrated in the Onderdonk patent with the improvements constituting the subject matter of the present invention applied thereto;

Fig. 11 is a front elevation of the decurling device shown in Fig. 10 and the immediately surrounding portions of the seaming machine;

Fig. 12 is an enlarged detached side elevation of the decurling device forming the subject matter of the present invention;

Fig. 13 is an enlarged front elevation of the decurling device detached;

Fig. 14 is an enlarged inverted plan view of the decurling device detached;

Fig. 15 is a sectional plan view taken on the line 15—15, Fig. 12;

Fig. 16 is a sectional elevation taken on the line 16—16, Fig. 12, and illustrating the device as removing the outwardly turning curl along the opposite edges respectively of the blank as illustrated in Fig. 7;

Fig. 17 is a view similar to Fig. 16 but showing the device as removing the inwardly turning curl from the opposite edges of the blank as illustrated in Fig. 8;

Fig. 18 is a perspective view of the device in operation; and

Figs. 19 and 20 are detached perspective views respectively of the main elements of the device.

As illustrated in Figs. 1 to 9 inclusive, the stocking with which the present invention is particularly concerned comprises a lower portion 1, which includes the leg and foot of the stocking; and an upper part 2 which includes the turned welt 3 composed, as usual, of two-ply fabric 3a and 3b joined together at and by the suture 4 and with a single ply portion 5 which, when composed of heavier thread than the lower leg portion or of a plurality of threads providing a heavier construction than the lower leg portion of the stocking is commonly referred to as a "shadow welt". The lower and upper portions 1 and 2 of the stocking are integrally connected together, preferably in accordance with the feature disclosed in the Hadfield patent above noted, along the coursewise extending line x—x, Fig. 1.

In the stocking shown in Fig. 1, the rough side R of the upper portion 2 is shown as being outermost and in the lower portion 1, including the leg, instep, etc. of the stocking, the smooth side S is outermost.

In the blank shown in Fig. 3, the rough side R of the upper portion 2 is shown as being uppermost and the smooth side S of the lower part 1 of the stocking blank is shown as being uppermost.

In preparing the stocking blank of Fig. 3 for seaming to form the stocking of Figs. 1 and 2, the points 10, 10 at the opposite sides respectively of the toe line 12 of the stocking are turned inwardly toward each other, as indicated by the arrows a, a, until the two points 10, 10 are in abutting relation to each other at the central point 11, whereupon the overlying and coinciding portions of the toe edge 12 disposed at opposite sides of the central point 11 are looped together.

The blank is then folded along its longitudinal axis indicated by the line y—y (Fig. 3) in the direction indicated by the arrows b—b until the points 13—13, 14—14, 15—15, 16—16, 17—17, 18—18, 19—19, 20—20, 21—21 and 22—22 along the opposite edges 25—25 respectively of the blank are brought into coinciding relation to each other, whereupon the then overlying coinciding edges 24, 24 of the heel lying between the points 14 and 15 at the opposite sides of the blank are looped together in the usual manner. The remainder of the edges 25, 25 of the blank are then seamed together from the points 10 to 75

the points 14 and from the points 15 to the points 22 and part way along the inner ply 3b of the turned welt 3, as usual.

In folding the blank along its axis $y-y$ in the manner described the smooth side S of the lower portion of the stocking is turned inwardly, as clearly indicated in Fig. 8, and as shown in said figure the opposite edges 25, 25 of the blank curl inwardly, from the points 10 to the points 14 and 10 from the points 15 to the points 20.

From the points 20 to the points 22 the opposite edges 25a, 25a of the upper portion 2 of the stocking turn outwardly as clearly illustrated in Fig. 7, and throughout the inner ply 3b of the turned welt 3 the edges 25a, 25a curl inwardly toward the corresponding edges of the outerly 3a of the welt, as illustrated in Fig. 4.

In a stocking constructed in the manner above described, it is necessary that the decurling device be capable of taking the curl out of the edges of the lower part of the stocking and the curl out of the edges of the upper part of the stocking in a single continuous operation without interruption, which cannot be accomplished by any prior art decurling device known to the applicant at the present time. Such operation may be successfully accomplished by the decurling device disclosed in Figs. 10 to 20 of the accompanying drawings, wherein an over-seaming machine of conventional type is generally indicated at 30, such machine being provided with the usual tangentially arranged horizontally disposed feed wheels 31, 31 in advance of the bite of which is disposed the decurling device generally indicated 35 by the reference character 32.

The decurling device 32 comprises an arm 33 which is pivoted at 34 to a bracket 35 carried by the machine 30, said arm being adapted to be swung from its operative position shown in full 40 lines in Fig. 10 to an inoperative position shown in broken lines in said figure.

The arm 33 is in the form of a flat plate, the opposite substantially parallel faces of which are recessed transversely of said faces near the outer 45 free end of the arm 33, as indicated at 36, 36. Below the recesses 36, 36, said opposite faces of the arm 33 are respectively provided with substantially flat surfaces 37 of irregular contour and which are disposed at an acute angle with 50 respect to each other in that they converge rearwardly from the front edge of the arm toward the rear edge thereof and the bite of the feed rolls 31, 31.

Intermediate the convergent flat faces 37, 37 the front edge of the arm 33 is provided with a 55 relatively sharp blade-like portion 38.

The base 39 of the relatively sharp edged section 38 of said arm is of lesser thickness than that portion of the arm lying between the forward portions of the converging flat surfaces 37, 37, and the forward arcuate edges 40 of the flat surfaces 37 are offset laterally with respect to the base 39 of the blade portion 38 of the arm, 60 thereby providing shoulders 41, 41 on the opposite sides of the arm adjacent the forward edges 40, 40 of the convergent flat surfaces 37, 37 respectively. The shoulders 41, 41 are disposed at an acute angle with respect to the side faces 65 of the blade portion 38 of the arm and to the faces 37, 37 thereof.

In front of the sharp edged portion 38 the arm 33 is provided with a broad nosed portion 42 which extends forwardly from the lower end of 70 the blade 38 between the flat face 37 on one side of

the arm and the flat face 37 on the opposite side of the arm. The upper surface 43 of the broad nose portion 42 is inclined forwardly and downwardly from the lower end of the sharp edge 38 of the arm, said top surface 43 being beveled inwardly and downwardly from each of the flat faces 37, 37 toward the central plane of the arm and the sharp edge 38 thereof, as indicated at 44, 44, whereby relatively sharp edges 45, 45 are provided where the upper forward edges of the flat 10 surfaces 37, 37 respectively intersect with the top surface 43 of the broad nose portion 42 of the arm 33.

Intermediate the rear end 46 of the inclined upper surface 43 of the broad nose 42 and the forward edges 47 of the shoulders 41 the flat surfaces 37, 37 are recessed, as indicated at 48.

Adjacent its free end the arm 33 is beveled from the lower edges 49, 49 of the flat surfaces 37, 37 respectively toward the extreme lower end 50 of the arm, said bevels 51 being in opposed relation to each other, whereby the lower edge 50 of the arm from the front to the back thereof is made relatively sharp.

Projecting forwardly beyond the front of the broad nose portion 42 of the arm 33, said arm is provided with a relatively sharp edged appendage 52 which curves upwardly from the lower edge 50 of the arm and then backwardly toward the front surface 53 of the broad nosed portion 42 of the arm.

Above the recesses 36, 36 the opposite sides of the arm 33 are provided with laterally extending lugs 55, 55 affording support for pivot pins 56, 56 on which are rockably mounted clamp arms 57, 57.

The lower portions of the clamp arms 57, 57 are shaped substantially in accordance with the contours of the flat surfaces 37, 37 of the supporting arm 33.

Each of the clamp arms 57 is provided with a front edge 59 which lies to the rear of the forward edge 53 of the adjacent flat surface 37 of said supporting arm 33; and a recess 58 corresponding to the recess 48 in said adjacent flat surface 37. The front portions 60 of the clamp arms 57, 57 are in the form of hooks, the upper pointed ends 61, 61 of which lie below the top rear edge 46 of the nose portion 42 of the arm 33.

The outer faces of the lower portions of the arms 57, 57 are beveled rearwardly in convergent 50 relation to each other as indicated at 62, 62 and the lower edges of said arms 57 being beveled inwardly as indicated at 63, 63.

The lower portions of the arcuate edges 69, 69 of the arms 57, 57 are beveled outwardly forming shoulders indicated at 70, 70 which are inclined in the direction opposite to the direction of the bevel of the corresponding lower portions of the arcuate shoulders 41, 41 formed on the arm 33. The forward edges of the hook-like portions 60 of the arms 57, 57 are beveled or rounded inwardly as indicated at 71, 71.

Above the pivots 56, 56 the arms 57, 57 are provided with extensions 73, 73 through which and the arm 33 extends a stud 74, said stud being rigidly secured intermediate its ends in the arm 33 with said ends projecting through openings formed in the extensions 73, 73 of the arms 57, 57.

Intermediate the extensions 73, 73 and extending through an opening formed in the arm 33 is a spring 75 which exerting outward pressure upon the extensions 73, 73 rocks the arms 57, 57 around their respective pivots 56, 56, thereby tending at all times to move the flat inner surfaces 77 at the lower ends of the arms 57 into flat contacting rela- 75

tion to the flat surfaces 37, 37 on the opposite side respectively of the arm 33.

Stop nuts 78, 78 threaded onto the outer ends of the stud 74 and bearing against the outer surfaces 5 of the lever extensions 13, 13 control the rocking movement of the levers 57, 57 about their pivots in one direction whereby the inner faces 11, 11 of the arms 57, 57 may be held in laterally spaced relation to the flat surfaces 37, 37 of the arm 33 in 10 accordance with the thickness of the fabric of the stocking blank, when desired.

In operation the arm 33 is moved into its full line position shown in Fig. 10 and the curled edges 25, 25 of the blank are respectively placed on opposite sides of the arm 33 between the flat surfaces 37, 37 thereof and the corresponding flat surfaces 11, 11 of the levers 57, 57, the converging beveled faces 51 and 63 of the arms 33 and 57 respectively facilitating the passage of the fabric 20 into the said position, it being noted that prior to sliding the two edges of the fabric simultaneously between the arms 33 and 57 the operator has manually uncurled a relatively small portion of the edges 25, 25 of the blank, after which as the 25 fabric is pulled by the feeding rolls 31, 31 the curl is automatically removed from the edges of the fabric by either the shoulders 41 on the arm 33 or the shoulders 78 on the arms 57 depending upon the direction in which the curl turns with respect 30 to the body of the fabric held between the flat surfaces 37 of the arm 33 and the flat surfaces 11 of the arms 57.

As clearly shown in Fig. 18, the back edges 25, 25 of the leg portion of the stocking are shown as being secured together with the fabric being drawn through the decurling device in the direction of the arrow by the feed rolls 31, 31 of the seaming machine, the seaming being effected from the heel toward the welt of the stocking in the 40 present instance, although the seaming may be effected in the opposite direction, that is, from the welt toward the heel of the stocking, if desired. As shown in said figure, the rough side of the leg fabric is outermost, causing the curl of 45 said leg portion to turn inwardly while the smooth surface of the welt or the top part 2 of the stocking is outermost causing the curl of the edges 25a thereof to turn outwardly from the plane of the fabric, the change in the curl from in to out being 50 clearly shown at 25b in said figure.

As the inturned curled edges 25 are drawn into the decurling device they rest primarily on the downwardly inclined surfaces 44 respectively of the nose section 42 of the device, the point of 55 protuberance 52 serving as a plow to separate the two ply of the fabric one from the other. As the curled edges 25 pass off the rear edges 46 of the nose section, they are separated by the blade 38 and pass to opposite sides of said blade 60 between the flat surfaces 37 of the arm 33 and the flat surfaces 11 of the arms 57, whereby said curled edges are directed against the arcuate downwardly and inwardly inclined shoulders 41 65 on the opposite sides of the arm 33 and as the fabric moves rearwardly between said flat surfaces the shoulders 41 engage the incurved edges 25 of the fabric and roll said edges outwardly due to the combined curvature and inclination of said shoulders, the curl finally being removed from 70 the edges of the fabric by the edges of the shoulders 41 at the points where the extreme edges of the fabric pass between the flat surfaces 37 and 11 at the intersections of the fabric with the curved edges 40 and 68 of the flat surfaces 37 and 75 11 respectively.

Passing laterally from each side of the arm 33 and through openings formed in the arms 57, 57 respectively are guide pins 80 which are used as gauges for determining the line inwardly from the flattened edges of the fabric at which 5 the needle or other element penetrates the two flattened edges of the fabric.

As the fabric continues to be fed in the direction of the arrow, Fig. 18, the straightening of the inner curled edges 25 is completed, whereupon 10 the twists 25b, 25b which connect the incurled edges with the outcurled edges 25a pass into the decurling device whereupon the upper surface of the nose portion 42 of the arm 33 loses contact with the curled edge. However, the outcurled edges 25a of the upper portion 2 of the stocking then ride over the outer ends 61 of the arms 57, 57 which function as guides in feeding the outcurled edges 25a between the arms 33 and 15 57. The edges 61 of the arms 57 in entering the 20 outcurled edges 25a at the twists 25b start to effect the decurling of said edges and from the points 61 the said curled edges pass on to the outwardly inclined shoulders 70 of the arcuate edges 69 of the arms 57 which complete the 25 decurling of the edges 25a in cooperation with the passing of the fabric between the flat surfaces 37 and 11 of the arms 33 and 57 respectively. The convergent relationship of the surfaces 37-37, 11-11 maintains the edges of the fabric 30 in flat parallel relation to each other and delivers the two edges of the fabric in such close relationship to each other at the bite of the rolls 31, 31 that recurling of the edges of the fabric is effectively eliminated between the rear edge of the decurling device and the bite of the feed rolls 31, 31. 35

With the decurling device as described, it is possible to lower the device so that the gauge pins 80 are much closer to the line at which the needle penetrates the fabric than has been possible heretofore. Consequently fewer wales along the opposite edges of the fabric are included in the seam formed by the seaming element, consequently a much finer and neater seam is made possible by the use of the attachment forming the 45 subject of the present invention than has been possible heretofore.

From the above, it will be quite clear that regardless of the direction in which the edges of the fabric may curl with respect to each other, 50 either inwardly throughout the full length of the stocking, outwardly throughout the full length of the stocking, or inwardly throughout part of the length of the stocking and outwardly throughout another part of the length of the stocking, the 55 device as described will remove the curl automatically without interrupting the feeding of the fabric by the feed rolls 31, 31 of the seaming machine and without any manual operations on the operator's part other than the usual primary decurling of a relatively small portion of the edges of the fabric when initially placing the stocking between the cooperating arms of the decurling device. 60

The so-called decurling devices of the prior art 65 do not remove the curl completely and as a consequence thereof the seaming needle passes through two thicknesses of fabric at each edge of the stocking blank, or four thicknesses in all, which produces a thick unsightly seam at the back of the finished stocking. With the arrangement of parts in the applicant's case as above described, the curl is completely removed and the edges are presented in flat lateral relation to each other to the needle of the seaming machine, thus there 70 75 75

are but two thicknesses of material for the needle to pass through, which makes it possible to stitch the blank real close to the selvage edges of the blank and this results in a very fine neat seam being produced up the back of the stocking, and which when the stocking is being worn permits the edges to assume a more or less flat edge to edge lateral abutting relation to each other producing what the applicant chooses to call an interlocked seam rather than the common overlock seam wherein the edges are seamed together while a portion of the curl or roll remains in the fabric.

I claim:

15 1. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, and a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade.

20 2. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, and a guide nose on the central element in advance of said separating blade between the planes of the flat faces on the opposite sides of said central element.

25 3. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, and a guide nose on the central element in advance of said separating blade between the planes of the flat faces on the opposite sides of said central

element, said guide nose having an upper surface transversely inclined in opposite directions outwardly from the median plane of said nose.

4. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, and a guide nose on the central element in advance of said separating blade between the planes of the flat faces on the opposite sides of said central element, said guide nose having an upper surface transversely inclined in opposite directions outwardly from the median plane of said nose and longitudinally inclined forwardly and downwardly from the lower front portion of said blade.

10 5. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, a guide nose on the central element in advance of said separating blade between the planes of the flat faces on the opposite sides of said central element, said guide nose having an upper surface transversely inclined in opposite directions outwardly from the median plane of said nose and longitudinally inclined forwardly and downwardly from the lower front portion of said blade and a relatively pointed protuberance projecting forwardly from the front of said guide nose.

15 6. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides re-

spectively of said dividing blade, a guide nose on the central element in advance of said separating blade between the planes of the flat faces on the opposite sides of said central element, said guide nose having an upper surface transversely inclined in opposite directions outwardly from the median plane of said nose and longitudinally inclined forwardly and downwardly from the lower front portion of said blade, and a relatively pointed protuberance projecting forwardly from the front of said guide nose, said fabric-engaging surfaces being in convergent relationship from said guide nose rearwardly to the back edge of the central element.

15. 7. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade therebetween, a guide nose on the central element in advance of said separating blade between the planes of the flat faces on the opposite sides of said central element, said guide nose having an upper surface transversely inclined in opposite directions outwardly from the median plane of said nose and longitudinally inclined forwardly and downwardly from the lower front portion of said blade, and a relatively pointed protuberance projecting forwardly from the front of said guide nose, said fabric-engaging surfaces being in convergent relationship from said guide nose rearwardly to the back edge of the central element, and the bottom edges of said central and side elements being beveled with the oppositely disposed bevels converging toward the lower edges of said flat fabric-engaging surfaces on the central and side elements respectively, and a guide nose on each of the side elements at opposite sides respectively of the guide nose on said central element.

15. 8. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, a guide nose on the central element in advance of said separating blade between the planes of the flat surfaces on the opposite sides of said central element, said guide nose having an upper surface transversely inclined in opposite directions outwardly from the median plane of said nose and longitudinally inclined forwardly and downwardly from the lower front portion of said blade, a relatively pointed protuberance projecting forwardly from the front of said guide nose, said fabric-engaging surfaces being in convergent relationship from said guide nose rearwardly to the back edge of the central element, and the bottom edges of said central and side elements being beveled with the oppositely disposed bevels converging toward the lower edges of said flat fabric-engaging surfaces on the central and side elements respectively, and a guide nose on each of the side elements at opposite sides respectively of the guide nose on said central element, said central and side elements being recessed intermediate the rear edges of the guide noses and the forward edges of the unrolling shoulders thereon.

shoulders on said central element extending from said flat surfaces thereof to the opposite sides respectively of said dividing blade, a guide nose on the central element in advance of said separating blade between the planes of the flat surfaces on the opposite sides of said central element, said guide nose having an upper surface transversely inclined in opposite directions outwardly from the median plane of said nose and longitudinally inclined forwardly and downwardly from the lower front portion of said blade, a relatively pointed protuberance projecting forwardly from the front of said guide nose, said fabric-engaging surfaces being in convergent relationship from said guide nose rearwardly to the back edge of the central element, and the bottom edges of said central and side elements being beveled with the oppositely disposed bevels converging toward the lower edges of said flat fabric-engaging surfaces on the central and side elements respectively, and a guide nose on each of the side elements at opposite sides respectively of the guide nose on said central element.

9. A device for simultaneously removing curl from two adjacently positioned knitted fabric edges comprising a central element and a pair of cooperating elements at opposite sides respectively of said central element, said central and side elements having laterally opposite flat fabric-engaging surfaces provided with forward coinciding arcuate edges, a curl unrolling shoulder at and cooperating with each of said coinciding edges and disposed at acute angles to said flat surfaces of the central and side elements respectively, a fabric-separating blade on said central element in a plane intermediate the planes of the fabric-engaging surfaces on the opposite sides respectively of said central element, said acute angle shoulders on said central element extending from said flat surfaces thereof to the opposite sides respectively of said dividing blade, a guide nose on the central element in advance of said separating blade between the planes of the flat surfaces on the opposite sides of said central element, said guide nose having an upper surface transversely inclined in opposite directions outwardly from the median plane of said nose and longitudinally inclined forwardly and downwardly from the lower front portion of said blade, a relatively pointed protuberance projecting forwardly from the front of said guide nose, said fabric-engaging surfaces being in convergent relationship from said guide nose rearwardly to the back edge of the central element, and the bottom edges of said central and side elements being beveled with the oppositely disposed bevels converging toward the lower edges of said flat fabric-engaging surfaces on the central and side elements respectively, and a guide nose on each of the side elements at opposite sides respectively of the guide nose on said central element, said central and side elements being recessed intermediate the rear edges of the guide noses and the forward edges of the unrolling shoulders thereon.
